FINGER CUFF

Abraham D. Cushing, Woodsville, N. H.

Application May 2, 1934, Serial No. 723,564

1 Claim. (Cl. 70—24)

This invention relates to devices for holding prisoners and it relates particularly to a finger cuff; the invention having for its object the provision of novel means whereby a finger of a captive may be clamped to securely hold it without creating pain unless effort is made to escape.

An object of this invention is to produce the novel means including a body and a member slidably with relation thereto whereby the space

10 between the body and the member may be adjusted to embrace fingers of different sizes, means being provided for holding the movable element in different positions of adjustment and in a manner to insure against accidental release of 15 the movable member, the invention further including means such as a key-operated lock or a lock otherwise operated for holding the last mentioned means against movement from its locking position.

20 A further object of this invention is to produce a body and a movable member slidably mounted therein, novel means being provided for holding the parts in assembled relation and in operative positions so that pressure on the movable member will speedily cause its adjustment for the purpose stated.

25 A still further object of this invention is to provide the body of the said device with an aperture for a finger of the operator in such relation to the end of the said member remote from the 30 slidable member as to permit the use of the device as a defensive weapon which may be regarded as a metal knuckle, it being understood that the said end of the body remote from the 35 slidable member has diverging arms which may serve the purpose of handles or hand grasps for the user and as extensions of the defensive portion of the body when it is to be used as a metal knuckle.

40 With the foregoing and other objects in view, the invention consists in the details of construction, and in the arrangement and combination of parts to be hereinafter more fully set forth and claimed.

45 In describing the invention in detail, reference will be had to the accompanying drawing forming part of this application, wherein like characters denote corresponding parts in the several views, and in which—

50 Figure 1 illustrates a view in elevation of a finger cuff embodying the invention;

Figure 2 illustrates a sectional view thereof; and

55 Figure 3 illustrates a detail view of a coacting member.

In the drawing, a body member 1 and a slideable shackle 1^a may be operated to reduce or increase the space between the end of the said member and the shackle. The member 1 is preferably made of metal with two longitudinally disposed bores 1^b and 1^c for a purpose to be presently explained. The shackle has its two end or leg portions slideable in the bores and one leg of the said shackle has serrations 2 on its inner surface. The other leg of the shackle has a slot 3 through which a pin 3' extends, the said pin being anchored in the body and operative to limit the outward movement of the shackle under the influence of the spring 1' seated in the bore 1^c and engaging the end wall of said bore and the 10 end of the shackle leg which moves in the bore. The body is also provided with a channel in which a ratchet or detent 8 is slidable, the said ratchet having a beveled end and the extremity thereof operates in conjunction with the ratchet 20 teeth 2 on one leg of the shackle. The ratchet is provided with a button or finger engaging member 4 operable in a slot 4' of the body member so that the ratchet may be moved against the action of the spring 8' located in the channel 25 and engaging the end of the channel and the said ratchet. The body is also provided with an aperture 6 and a fluted end 7 including the arms 10 and 14. When the user of the finger cuff desires to use it as a defensive weapon, the 30 shackled end thereof will be placed in the palm of the hand and one finger projected through the aperture 6 while the other fingers will engage the concaved surfaces of the arms 10 and 14 so that in this use of the device, the outer surfaces 35 of the parts 7, 10, and 14 may be said to constitute metal knuckles.

As a means for preventing accidental movement of the ratchet or the movement thereof by unauthorized persons, the said ratchet has a 40 notch 12 in its side and a locking bolt 9 is located in a channel approximately at right angles to the ratchet and is slideable therein toward and away from the said ratchet under the influence of a key to be applied to the keyhole 5 in a 45 barrel located in a hole 5' in the said member. The locking bolt 9, under the influence of the key, may be moved into engagement with the ratchet so that its end lies in the notch 12 thereof and when unlocked, the locking bolt will 50 assume the position in which it appears in Figure 2. The locking bolt is frictionally retained in the different positions of adjustment by a spring 13 as shown in Figure 2 engaging the 55

edge of said bolt and the wall of the slot in which the locking bolt moves.

I claim:

5 In a finger cuff, a body having a handle comprising oppositely projecting arms and an interposed fluted portion, the said body having bores, a transversely disposed channel intersecting one of the bores, a shackle having two end portions

movable in the bores, ratchet teeth on the surface of one of said end portions facing the said channel, a ratchet in the channel engageable with the ratchet teeth, means for urging the ratchet into engagement with the teeth, and means for retaining the ratchet against movement when in engagement with the teeth.

6 ABRAHAM D. CUSHING.
